UNITED STATES PATENT OFFICE

2,092,411

DOOR CLAMP

Carl August Anderson, Montclair, N. J., assignor
of one-half to Robert R. Abrams, East Orange,
N. J.

Application December 12, 1936, Serial No. 115,519

2 Claims. (Cl. 20—38)

This invention relates to improvements in clamps for doors and is particularly applicable to doors which are exposed to the elements, such as garage doors and the like.

5 It has been found, in practice, that no matter how well such doors may be originally constructed, their exposure to the elements eventually causes the parts of the doors to separate where they are joined together.

10 It is an object of the invention to provide a clamp adapted to be secured to opposite edges of a door and having means for drawing the door edges together to restore and clamp the parts of the door to their original position.

15 A further object of the invention is to provide a device of the character described comprising essentially two clamp sections of simple construction and economical to manufacture, adapted to be readily secured to a door and adapted to clamp 20 the parts of the door together in a simple, efficient and rapid manner.

25 A further object of the invention is to provide a device of the character described having adjustable means for drawing the door edges together to the exact degree required, from time to time.

These and other advantageous objects, which will later appear, are accomplished by the simple and practical construction and arrangement of parts hereinafter described and exhibited in the 30 accompanying drawing, forming part hereof, and in which:

Fig. 1 represents a perspective view of a door having two clamps embodying my invention secured thereto,

35 Fig. 2 represents a perspective view of a clamp embodying my invention, and

Fig. 3 represents an enlarged fragmentary sectional view taken on lines 3—3 of Fig. 1.

40 Fig. 4 represents an exploded fragmentary perspective view of a modified form of my invention, and

Fig. 5 represents a fragmentary top plan view of the same parts shown in assembled position.

45 Referring to the drawing, the clamp of my invention is shown to comprise a pair of sections 5, 6. Each section has an end 7 angularly directed and bent back upon itself to provide a lug 8 of the requisite thickness and strength. 50 The other end of each section is angularly directed at 9 and then bent back at 10 parallel to the section to provide a U-shaped end. The U-shaped ends of the clamp sections are adapted to be secured to opposite edges 12 of the door 13 by screws 14 or other suitable means. The lug 8 of section 6 is provided with an aperture 15 through which a bolt 16 freely passes and engages the threaded aperture 17 of lug 8 of section 5 (see Fig. 3). By manipulating the bolt 16, the sections 5 and 6 are brought together and the op-

posite edges of the door 13 are drawn together to the degree required to restore the door parts to their original position.

The clamp sections are provided with elongated slots 19 through which screws 18 or the like are passed for engagement with the door 13.

If it is desired to draw the clamp sections further together, it is merely necessary to "back up" a few turns on the screws 18, and when the clamp bolt 16 has been manipulated to the desired degree (as indicated in dotted lines, Fig. 3) the screws 18 are again turned down.

In the modification shown in Figs. 4 and 5, the clamp section 6 is provided with a suitable bearing 20 adapted to receive a hinge pin 23 carried by a similar bearing 22 formed on the plate 21, said plate being preferably secured to the door casing 24.

By this arrangement the usual door hinges may be dispensed with—the section 6 and its bearing 20 constituting one-half of the hinge, the plate 21, its bearing 22 and pin 23 constituting the other half of the hinge. It will be obvious that this arrangement results in a substantial saving in cost of labor and material, when two clamps embodying this modification are secured to a door as shown in Fig. 1.

By the device described, the door edges may be minutely and accurately drawn together to restore the parts of the door to their original position and further adjustments may be readily made from time to time as required.

The foregoing disclosure is to be regarded as descriptive and illustrative only, and not as restrictive or limitative of the invention, of which obviously embodiments may be constructed, including many modifications, without departing from the spirit and scope of the invention as set forth in the appended claims.

Having thus described my invention, what I claim as new and desire to secure by Letters Patent, is:

1. A device of the character described comprising a pair of clamp sections adapted to be secured to a door, said clamp sections being provided with elongated slots through which screws are adapted to be passed, and being further provided with outwardly extending lugs, and means engageable with said lugs to draw the clamp sections together.

2. A device for bracing doors and the like, comprising a pair of bars, each of said bars having one end thereof bent to provide a U-shape, and the other end thereof bent at right angles and then bent back upon itself to provide a lug, each of said bars having elongated slots through which screws can be passed, one of said lugs being threaded, and a threaded bolt passing through said lug for drawing the bars together.
